UNITED STATES PATENT OFFICE.

CHARLES POHL, OF LOS ANGELES, CALIFORNIA, ASSIGNOR TO GLOBE MANUFACTURING COMPANY, OF LOS ANGELES, CALIFORNIA, A CORPORATION OF ARIZONA.

ENGINE-STARTER.

1,302,213.

Specification of Letters Patent. Patented Apr. 29, 1919.

Application filed September 9, 1918. Serial No. 253,193.

To all whom it may concern:

Be it known that I, CHARLES POHL, a citizen of the United States, residing at Los Angeles, in the county of Los Angeles and 5 State of California, have invented a new and useful Engine-Starter, of which the following is a specification.

This invention pertains to a device of the character employed in starting into operation internal combustion engines and refers 10 particularly to improvements over my prior patent for engine starter No. 1,149,783, dated August 10, 1915.

In the patented starter more or less difficulty arises from the fact that if the engine 15 back-fires the pawl is not thrown out of commission quickly enough and consequently is more or less injured by the back thrust of the ratchet teeth. Besides this it is clear 20 that if the pawl is not thrown out quickly enough it tends to be rotated with the ratchet member when back-fire takes place and thus causes shock and possibly injury to the operator. In said former patented device the 25 foot of the operator was employed to operate the device and this present device may be operated in the same manner or otherwise as desired.

An object of the invention is to overcome 30 the above noted difficulty.

Further objects and advantages will appear in the subjoined detailed description.

The accompanying drawings illustrate the invention:

35 Figure 1 is a side elevation of a starter built in accordance with the provisions of this invention, a portion of the shaft being broken away to contract the view and the cap being shown in vertical mid section so as to 40 expose the parts within.

Fig. 2 is a sectional elevation taken on a plane normal to the direction of sight in looking at Fig. 1.

Fig. 3 is an elevation from line indicated 45 by x^3-x^3 , Fig. 2, the cap being omitted.

Fig. 4 is an elevation from line indicated by x^4-x^4 , Fig. 2, the cap being omitted.

There is provided a shaft 1 which may be connected at its rear end by a coupling 2 to 50 the shaft, not shown, of the engine with which the device is to be used. The shaft 1 is provided at its forward end with a transversely extending pin 3 so that a starter crank, not shown, can be used in an emergency for cranking the engine. The shaft 1

is journaled in a bearing 4 of a housing indicated in general by the character 5. This housing 5 may be fastened by any suitable means to the frame of the engine or automobile on which the device is to be used. In 60 the instance shown in the drawings the housing 5 is provided at its periphery with laterally projecting ears 6 through which bolts may be passed to bolt the housing in place.

The front of the housing 5 is in the form 65 of a bell-shaped cap 7 which may be fastened in place by screws 10 or their equivalents. The cap 7 is provided at its outer end with an orifice 8 normally closed by a detachable cover 9. This cover 9 may be fastened in place by any well known means so that it may be detached in order that a crank 70 may be applied to the front end of the shaft 1 to turn said shaft, if for any reason the starter should get out of order so as to necessitate the cranking of the shaft 1 by hand 75 in a manner well understood in the art pertaining to internal combustion engines.

Fastened by the screws 10 to a flange 11 of the housing 5 is a spring support 12 provided with a spring chamber 13 in which is accommodated a clock spring 14. The spring 14 is fastened at one end by a screw 15 or its equivalent to the peripheral wall 80 of the chamber 13 and the opposite end of 85 said spring is fastened by a screw 16 or its equivalent to a hub 17 journaled at 18 on the shaft 1. The hub 17 is provided with a radially extending flange 19 fastened by screws 20 or their equivalents to a cupped 90 member 21, the flange 19 and cupped member 21 together forming a rotary member or inner housing for a ratchet wheel 22 which is keyed at 23 to the shaft 1. The teeth 24 of the ratchet wheel are designed to be engaged 95 by a pawl 25 pivoted at 26 to the cupped member 21. Thus the pawl 25 is rotatively mounted on the shaft 1 and the spring 14

yieldingly holds the pawl against rotation around the shaft. The pivoting of the pawl 100 25 is such that counter-clockwise rotation of the ratchet wheel in Fig. 3 will tend to push the pawl 25 out of engagement with the teeth of the ratchet wheel. This construction is just the reverse of that disclosed in the above 105 mentioned patent for in said patent the pawl is so pivoted that counter-clockwise rotation of the ratchet wheel does not tend to throw the pawl out of engagement with the teeth, a spring being solely relied upon to retract the 110

pawl. In the former construction when the engine back-fired it caused rotation of the ratchet wheel against the pawl and owing to the inertia of the spring, said spring did not 5 act quickly enough to retract the pawl and therefore the ratchet wheel delivered a blow on the pawl, sometimes sufficiently hard to break the pawl or the teeth of the ratchet wheel. By the construction disclosed above 10 such breakage is obviated.

The pawl 25 is normally pressed outward from the ratchet wheel and held out of commission by a spring 27 fastened by screws 28 or their equivalents to the perimeter of 15 the cupped member 21. The free end of the pawl 25 is engaged by a lever or arm 29 pivoted at 30 to the cupped member 21. When this lever 29 is swung inward it 20 forces the pawl 25 toward the ratchet wheel to engage one of the teeth of said ratchet wheel. Pivoted at 30 to the arm 29 is a flexible connection 31 which in the instance shown is in the form of a chain. This 25 chain passes through a port 32 in the housing 5 and is adapted to be connected to any suitable operating mechanism whereby a pull may be exerted on the connection 31 for 30 operation thereof to cause rotation of the shaft 1 in a manner to be hereinafter described.

The spring support 12 is provided with radially extending oil ducts 32' which are adapted during rotation of the hub 17 to communicate at their inner ends with an oil 35 duct 33 in the hub 17 so that oil may be supplied by way of said ducts to the journal 18. The housing 5 is provided with a radially extending oil duct 34 adapted to communicate at its inner end with a duct 35 in the 40 journal 4 so that oil may be supplied to said journal. The duct 34 extends to the perimeter of the housing 5 and is ordinarily closed by a plug 36 which may be removed when desired to supply oil to the duct 34.

45 Projecting in from the inner face of the housing 5 is a lug 37 adapted to act as a stop against a shoulder 38 of the housing 19, 21, to limit retractive movement caused by the spring 14.

50 In practice, assuming that the coupling 2 connects the shaft 1 to the engine shaft, not shown, of an internal combustion engine, if it be desired to start the engine into operation, the operator will cause a pull 55 to be exerted on the connection 31 by foot-operated or other suitable mechanism, not shown, so as to swing the arm 29 inward toward the axis of the starter. The arm 29 in this movement pushes the pawl 25 into engagement with the ratchet wheel. The operator continues to exert a pull on the flexible connection 31 and thereby ro-

tates the pawl 25 and with it the ratchet wheel in the direction indicated by the arrow *a*, Fig. 3. Turning of the pawl causes 65 turning of the hub 17 which operates to wind the spring 14 so as to store up power in said spring. The ratchet wheel turns the shaft 1 so as to rotate the engine shaft and start the engine into operation. The engine 70 will thereupon become self-operating in a manner well understood in the art pertaining to internal combustion engines and as soon as self-operation becomes evident the operator will discontinue pulling on the 75 connection 31 whereupon the stored up power of the clock spring 14 will become operative to cause rotation of the hub 17 in a direction opposite to that indicated by the arrow *a* Fig. 3, so as to rotate the cupped 80 member 21 and with it the pawl 25 and ratchet wheel to thereby retract the flexible connection 31 to the position shown in Fig. 3 ready for another operation the next time the engine is to be started. 85

If the engine should back-fire it would tend to cause counter-clockwise rotation of the ratchet wheel and, therefore, before the spring 27 could come into action to retract the pawl 25, even when the operator has released the flexible connection 31, the ratchet wheel will throw out the pawl 25 so that such counter-clockwise rotation will be perfectly free and no injury result to the ratchet teeth, pawl or operator. 90

95 I claim:

An engine starter comprising a housing, a shaft journaled in the housing, a rotary member journaled on the shaft, a pawl pivoted to the rotary member, a ratchet wheel fixed to the shaft and adapted to be engaged by the pawl, a spring connected at one end with the housing and at its opposite end with the rotary member to cause the ratchet wheel to be turned in one direction when the pawl is in engagement with the ratchet wheel, the pawl being adapted to be thrown out of engagement with the ratchet wheel by turning of said wheel in the opposite direction, an arm pivoted to the rotary member and adapted to engage the pawl to move the pawl toward the ratchet wheel, means to yieldingly hold the pawl out of engagement with the ratchet wheel, and a flexible connection attached to the arm whereby the 110 arm may be swung against the pawl and rotated about the shaft. 115

Signed at Los Angeles, California, this 4th day of September, 1918.
